INVENTOR -
George F. Voight

UNITED STATES PATENT OFFICE.

GEORGE F. VOIGHT, OF OAKLAND, CALIFORNIA, ASSIGNOR TO ECONOMY PRODUCTS CORPORATION, A CORPORATION OF CALIFORNIA.

FURRING NAIL.

Application filed September 19, 1923. Serial No. 663,651.

My invention relates to improvements in furring nails particularly useful for securing stucco reinforcement to the wall sheathing of frame buildings, although useful for other purposes.

One of the objects of the present invention is the provision of a cup-shaped spacing element having a bottom provided with an opening through which projects the forward end of a driven element, the margin of said opening intended to engage the sides of said driven element with sufficient diametrical contractile tension to cause said spacing element to be normally frictionally locked on said driven element against accidental movement relative thereto, but longitudinally slidably thereon against the resistance of said diametrical contractile tension of the spacing element against the driven element, when said spacing element is disposed against a support and the driven element operatively driven thereinto a proper distance.

A further object is the provision of a cup-shaped spacing element having a bottom concaved on the outer side and convexed on the inner side and provided with a central opening in axial alignment with said spacing element.

A still further object is the provision of a cup-shaped spacing element having a concavo-convex bottom provided with a central opening, the margin of which having an inwardly projecting hub, the latter adapted to engage the sides of the driven element for holding it in said opening in axial alignment with said spacing element.

A still further object is the provision of a spacing element cylindrical in form and having a bottom with a central opening therethrough, cooperable with a driven element having its upper end formed into a side arm or hook adapted to operatively engage and bind a reinforcement wire on the spacing element, the free end of said side arm extending outwardly beyond the rim of the spacing element.

With the foregoing and further objects and purposes in view which will appear as the description proceeds, my invention resides in the combination and arrangement of parts and in the details of construction hereinafter described and claimed, it being understood that

changes in the precise embodiment of the invention herein disclosed can be made within the scope of what is claimed without departing from the spirit of the invention.

In the accompanying drawings:

Figure 1 is a side elevation of a furring nail constructed in accordance with my invention, in its initial position for projection into the wall sheathing, also showing a cross section of a fragment of the reinforcement;

Figure 2 is a vertical sectional view of the device in its initial position against the wall sheathing;

Figure 3 is a side elevation, showing the nail in its final position as projected into the wall sheathing, with a wire forming a portion of the reinforcement clamped between the spacing element and a projection on the upper end of the nail;

Figure 4 is a plan view of the furring nail, a section of wall sheathing and a fragment of the metal reinforcement;

Figure 5 is a cross section on line 5'-5', Fig. 2;

Figure 6 is a view on line 6'-6', Fig. 1;

Figure 7 is a side elevation of the furring nail in a modified form to the extent that the spacing element is inverted relative to the shank of the nail;

Figure 8 is a sectional elevation of the modified form;

Figure 9 is an enlarged view of the device on line 9'-9', Fig. 7; and

Figure 10 is a vertical section approximately on line 10'-10', Fig. 3.

Referring to the drawings in detail, throughout which like reference characters designate like parts:

The numeral 1 designates the wall sheathing, 2 the furring nail, and 3 the stucco reinforcement.

The wall sheathing 1 comprises the usual siding boards nailed to the studding and frame timbers of the wall of a building preparatory to the application of the stucco composition; the boards preferably disposed in closely laid order.

The reinforcement 3 comprises, preferably, wire cloth commonly known as "poultry netting", and is intended to be secured to the wall sheathing at a distance outwardly therefrom and at suitable intervals, by means of

the furring nails 2; the "poultry netting" forming reinforcement for the stucco composition, the latter adapted to be spread on the wall sheathing and on and around the reinforcement.

The furring nail 2 comprises a cylindrical shaft or driven element 4 having at its upper end a downwardly projecting side arm 5, and a spacing element 6.

10. The spacing element, which is preferably pressed from sheet metal, is cup shaped and provided with a concavo-convex bottom 7, the latter having an inwardly projecting central hub 8 provided with a central vertical opening 9, through which projects the shaft 4. The dishing inwardly of the bottom 7 provides an annular upstanding marginal rim 10 arcuated in cross section in a vertical plane.
15. In the regular or preferred form of the invention, the cup is inverted, the shaft 4 entering the cup from the bottom, while in the modified form, shown in Figs. 7, 8 and 9, the shaft is entered from the upper or open end of the cup. This reversing of the ends of the cup is the only difference between the regular and the modified forms of the invention.
20. In the regular or preferred form of the invention, the cup is inverted, the shaft 4 entering the cup from the bottom, while in the modified form, shown in Figs. 7, 8 and 9, the shaft is entered from the upper or open end of the cup. This reversing of the ends of the cup is the only difference between the regular and the modified forms of the invention.
25. The spacing element 6 is cylindrical in cross section and has the rim of its upper end preferably scalloped thereby forming indentations 11 between elevated portions 12.

The hub 8 is intended to embrace the shaft 4 with sufficient contractile tension, or, in other words, the shaft 4 is intended to fit sufficiently tight in the opening 9, so that the spacing element 6 will be normally locked on the lower end of the shaft against accidental movement when the nail is handled as 30 when disposing it in its position on the wall sheathing, but vertically slideable thereon when the spacing element is disposed in operative engagement with the sheathing and the shaft driven thereto a proper distance.

40. To apply my furring nail for securing the reinforcement wire 3 to a wall: After having disposed the reinforcement across the face of the sheathing, the upper end of the nail is grasped by the operator and its forward end, together with the spacing element, projected through one of the meshes of the reinforcement and engaged with the sheathing with the shank of the nail along side one of the wires of the mesh (see Figs. 1 and 2), the head of the nail is then impinged by 45 means of a hammer or like hand tool and the shank 4 projected slidably forwardly through the hub 8 and into the wall sheathing 1 until the crotch of the side arm 5 engages the reinforcement wire 3 and forces it down tightly against the spacing element 6.

The operation for applying the nail, is essentially the same in either of the forms described. The only difference being that 50 in the regular form the wire is received on

the annular rim 10, while in the modified form the wire is adapted to be received in the indentations 11.

It will be observed that the reinforcement wire 3 is received on opposed portions of the rim 10 of the spacing element (see Fig. 10), and that the side arm 5 engages the wire between said portions. This arrangement for separating the lower bearing points of the wire, permits of certain downward flexion thereof, and thereby provides considerable latitude to the vertical movement of the shank 4 relative to the spacing element, and prevents any accidental crushing of the latter or of forcing it part way into the wall sheathing when the shank is driven in excess of that required for properly securing the reinforcement to the wall.

It is obvious that any number of the furring nails may be employed for securing the reinforcement, and that the nails may be used for securing reinforcement other than "poultry netting".

I claim:—

1. In a furring nail of the character described, a cup-shaped spacing element having a concavo-convex bottom provided with a central opening, and a coacting driven element projecting axially through said spacing element and through said opening, said driven element having a side arm at its upper end, said driven element operatively slideable through said opening, whereby the free end of said side arm may be caused to be disposed along the outside of said spacing element below the upper end thereof.

2. A wire fastener comprising a tubular member having a bearing face on one end thereof and a circular depression of shallow depth formed concentrically within the opposite end of the said tubular member; and a nail having the pointed end thereof arranged concentrically in the depression whereby the head of the nail will confine wire material in the shallow depth depression formed in the tubular member.

3. A driven element, and a spacing element comprising, means disposed on opposite sides of said driven element in spaced relation thereto, said means adapted to seat against a support, an intermediately disposed portion integrally secured to said means, said portion having an opening through which said driven element projects, and means on said portion at the margin of said opening, said last named means bearing against the periphery of said driven element to normally resist removal therefrom, said last named means adapted to be disposed in spaced relation to said support.

4. A driven element, a spacing element having portions disposed on opposite sides of said driven element and in spaced relation thereto, the lower ends of said portions adapted to bear against the wall of a structure, an

- intermediate member integrally connecting the upper ends of said portions together, said member having an opening through which said driven element projects and against the 5 margin of which it bears to normally resist removal therefrom, and means on the inner side of said member at the margin of said opening, said means bearing against the surface of said driven element below said opening to normally prevent lateral tilting of said driven element relative to the spacing element, said means adapted to be disposed in spaced relation to said wall.
- 10 5. A furring nail comprising a tubular member, a head at one end thereof, said head having an opening, a driven element projecting through said opening and through said tubular member, and means on the inner side of said head at the margin of said opening, 15 said means arcuated in a plane extending at right angles across the axis of said driven element, said means bearing against said driven element below said head.
- 20 6. In a furring nail of the character described, a substantially cylindrical spacing element, and a substantially cylindrical nail engaging hub concentrically mounted inside of the spacing element.
- 25 7. In a furring nail of the character described, a substantially cylindrical spacing element provided with a concavo-convexed
- bottom, and a substantially cylindrical nail engaging hub carried by the concavo-convexed bottom and concentrically spaced inside of the spacing element.
- 30 8. In a furring nail of the character described, a substantially cylindrical spacing element provided with a bottom, and a substantially cylindrical nail engaging hub carried by the bottom and concentrically spaced inside of the spacing element.
- 35 9. In a furring nail of the character described, a substantially cylindrical spacing element, and a substantially cylindrical nail engaging hub mounted inside of the spacing element.
- 40 10. In a furring nail of the character described, a substantially cylindrical spacing element provided with a closure at one end, and a substantially cylindrical nail engaging hub carried by the closure and concentrically spaced inside of the spacing element.
- 45 11. In a furring nail of the character described, a substantially cylindrical spacing element provided with a closure at one end, and a substantially cylindrical nail engaging hub carried by the closure.
- 50 In testimony of the foregoing being my own, I have hereunto affixed my signature this 11th day of September, 1923.

GEORGE F. VOIGHT.
